DESIGN FOR A CONTOUR TRACER

Wallace P. Hoverder, Kansas City, Mo.

Application November 22, 1939, Serial No. 88,406

Term of patent 7 years

To all whom it may concern:

Be it known that I, Wallace P. Hoverder, a citizen of the United States, residing at Kansas City, in the county of Jackson and State of Missouri, have invented a new, original, and ornamental Design for a Contour Tracer, of which the following is a specification, reference being had to the accompanying drawing, forming a part thereof.

Fig. 1 is a perspective view of the contour tracer, showing my design.

Fig. 2 is a side elevational view thereof.

Fig. 3 is an end elevational view of one end thereof; and,

Fig. 4 is an end elevational view of the other end thereof.

I claim:

The ornamental design for a contour tracer, as shown.

WALLACE P. HOVERDER.
